(57) **CLAIM**

The ornamental design for a personal flotation device, as shown and described.

DESCRIPTION

FIG. 1 is a top front perspective view of a personal flotation device in accordance with the new design;

FIG. 2 is a top rear perspective view thereof;

FIG. 3 is a bottom front perspective view thereof;

FIG. 4 is a top elevation view thereof;

FIG. 5 is a bottom elevation view thereof;

FIG. 6 is a front elevation view thereof;

FIG. 7 is a back elevation view thereof;

FIG. 8 is a side elevation view thereof;

FIG. 9 is a side elevation view thereof, for the side opposite that of FIG. 8;

FIG. 10 is a top front perspective view of a second embodiment thereof; and,

FIG. 11 is a bottom front perspective view of the second embodiment.

The broken lines shown in the drawings are only provided to illustrate the environment of the design and form no part of the claimed design.

1 Claim, 9 Drawing Sheets

FIG. 5
